APPARATUS FOR THE CONTROL OF HIGHWAY CROSSING SIGNALS

Charles W. Bell, Forest Hills, Pa., assignor to The Union Switch & Signal Company, Swissvale, Pa., a corporation of Pennsylvania

Application January 31, 1939, Serial No. 253,831

4 Claims. (Cl. 246—130)

My invention relates to apparatus for the control of highway crossing signals, and has for an object the provision of novel and improved means to provide directional control of a highway crossing signal for a track over which trains move in each direction, where conditions are such that the control track sections for the signal cannot extend through the highway but are separated from each other at the crossing by a section of 5 track longer than a single car or light engine.

Other objects and advantages of my invention will appear as the specification progresses.

I shall describe one form of apparatus embodying my invention, and shall then point out 15 the novel features thereof in claims.

The accompanying drawing is a diagrammatic view of a preferred form of apparatus embodying my invention.

Referring to the drawing, the reference characters **1** and **1a** designate the track rails of a stretch of railway track over which traffic moves in both directions, and which is intersected at grade by a highway **H**. Located adjacent the intersection is a highway crossing signal, designated by the reference character **S**. Signal **S** may take any one of several forms, and as here shown is an audible signal in the form of an electric bell.

The track rails **1** and **1a** are divided by means 30 of the usual insulated track joints **2** into the track sections **D—E** and **F—G**, which sections extend in opposite directions from the intersection. The sections **D—E** and **F—G** are provided with track circuits comprising in each in- 35 stance a suitable source of current, such as a track battery **3**, connected across the rails at one end of the section, and a track relay, designated by the reference character **1' TR** or **2' TR**, connected across the track rails at the other end.

The section **E—F**, which is intermediate the sections **D—E** and **F—G** and which contains the highway **H**, is not provided with a track circuit, it being assumed that local conditions at the intersection render the establishment of a track 40 circuit for that section impossible or inadvisable. The section **E—F** I shall assume to be longer than the length of a single car or light engine operating on the tracks **1** and **1a**, while the sections **D—E** and **F—G** I shall assume to be sufficiently 45 long enough to provide an adequate warning period to highway users of the approach of a train to the intersection.

The reference character **XR** designates an interlocking relay for controlling the operation 50 of signal **S**. Relay **XR** comprises a first winding

W1 and a second winding **W2**, and may take any one of the well-known forms of interlocking relays characterized by the fact that the first winding only of the two windings to be successively deenergized is permitted to open or close its front or back control contacts, the second winding of the interlocking relay to be successively deenergized being released to an interlocked position wherein its front and back control contacts are latched up and are held re- 10 spectively closed or open.

The immediate operating circuit for signal **S** passes from one terminal **B** of a suitable source of current, such as a battery not shown, through back contact **4** of winding **W1** or back contact **5** 15 of winding **W2**, and the winding of signal **S** to the other terminal **C** of the source of current.

The reference character **TER** designates a time element device for at times controlling winding **W1** or **W2** of relay **XR**. The device **TER** may 20 take any one of many forms well known to the art, and as here shown is a thermal relay provided with a normally open contact **6**, which contact is closed in a predetermined time interval after relay **TER** is energized. Relay **TER** 30 is provided with three energizing circuits, a first circuit of which passes from terminal **B** through back contact **7** of winding **W1** or back contact **8** of winding **W2**, front contact **9** of relay **2' TR**, front contact **10** of relay **1' TR**, and the winding **35** of relay **TER** to terminal **C**; a second path of which passes from terminal **B** through back contact **11** of winding **W1**, back contact **12** of relay **2' TR**, front contact **13** of relay **1' TR**, and the winding of relay **TER** to terminal **C**; and a third 40 path of which passes from terminal **B** through back contact **14** of winding **W2**, front contact **15** of relay **2' TR**, back contact **16** of relay **1' TR**, and the winding of relay **TER** to terminal **C**.

The apparatus embodying my invention is in 45 its normal condition when no trains are operating on the track rails **1** and **1a** intermediate the points **D** and **G**. In this normal condition of the apparatus, as shown in the drawing, relays **1' TR**, **2' TR** and windings **W1** and **W2** of **XR** are 50 energized, and relay **TER** and signal **S** are deenergized. Winding **W1** of relay **XR** is normally energized over a stick circuit which may be traced from terminal **B** through front contact **17** of winding **W1**, front contact **18** of relay **1' TR** and the winding **W1** of relay **XR** to terminal **C**. Winding **W2** is normally energized over a stick circuit which may be traced from terminal **B** through front contact **19** of winding **W2**, front 55

60

contact 20 of relay 2TR, and winding W2 of relay XR to terminal C.

In describing the operation of the apparatus embodying my invention, I shall assume that an 5 eastbound train, that is, a train operating from left to right in the drawing, enters section D—E so that relay 1TR is shunted and releases. When this happens, front contact 18 of relay 1TR is opened to open the stick circuit just traced for 10 winding W1, with the result that winding W1 releases to close its back contact 4 and thereby complete the operating circuit for signal S, so that signal S becomes energized to display its 15 warning indication to highway users of the approach of the train to the intersection. Front contact 17 of winding W1 is also opened when winding W1 releases, so that the stick circuit for winding W1 is opened at that point. Back contacts 7 and 11 of winding W1 are also closed, 20 to prepare respectively the first and second energizing circuits for relay TER.

In the event that the train is long enough to bridge both sections D—E and F—G, the entrance of the train on section F—G and consequent shunting of relay 2TR results in relay 2TR 25 releasing. When this happens, front contact 20 of relay 2TR is opened to open the stick circuit previously traced for winding W2 with the result that winding W2 is deenergized and releases 30 its armature to its interlocked position, wherein front contact 19 of winding W2 remains closed and back contacts 5, 8 and 14 of winding W2 are prevented from closing.

When the train vacates section D—E, relay 35 1TR picks up to close its front contacts 18 and 13, the closing of front contact 18 of relay 1TR preparing the stick circuit for winding W1, while the closing of front contact 13 completes the 40 second energizing circuit for relay TER, which circuit, as pointed out hereinbefore, includes back contact 11 of winding W1, back contact 12 of relay 2TR, and front contact 13 of relay 1TR. Relay TER at the end of its predetermined time 45 interval of energization closes contact 6 to establish a pick-up circuit for winding W1, which circuit may be traced from terminal B through front contact 19 of winding W2, contact 6 of relay TER, front contact 18 of relay 1TR, and the winding W1 of relay XR to terminal C. Winding W1 picks up its pick-up circuit to open 50 back contacts 4 and 11, the opening of back contact 4 interrupting the operating circuit for signal S, and the opening of back contact 11 opening the second energizing circuit for relay 55 TER. The picking up of winding W1 of relay XR also closes front contact 17 to complete its previously traced stick circuit, with the result that winding W1 is held energized over that circuit when contact 6 of relay TER is opened upon 60 the deenergization of that relay. It is to be noted that since winding W2 is released to its interlocked position prior to winding W1 picking up, directional control of the signal S is established whereby the operation of the signal is not 65 effected by a train operating through a control section in receding from the intersection.

When the train vacates section F—G, relay 2TR picks up to close front contact 20 and thereby complete the stick circuit for winding W2, 70 with the result that winding W2 picks up so that the apparatus is restored to its normal condition.

In the event that the eastbound train operating over tracks 1 and 1a is short so that it does not bridge sections D—E and F—G, then the 75 train will vacate section D—E and relay 1TR

will pick up, prior to the train entering section F—G. When the train vacates section D—E and relay 1TR picks up, the first energizing circuit for relay TER is completed, which circuit includes back contact 7 of winding W1, front contact 9 of relay 2TR and front contact 10 of relay 1TR. Relay TER becomes energized, but since relay TER does not close its contact 6 until the expiration of its predetermined time interval, the train will ordinarily enter section F—G to effect 10 the deenergization of relay 2TR and of winding W2 to its interlocked position, prior to contact 6 of relay TER closing.

The release of relay 2TR, when the train enters section F—G, and the consequent release of 15 winding W2 of relay XR to its interlocked position, results in the opening of the first energizing circuit for relay TER, but relay TER is held energized over its previously traced second energizing circuit. The operation of the apparatus 20 with the short train on section F—G is now substantially similar to the operation for the long train on section F—G. That is to say, relay TER is energized and closes its contact 6 at the expiration of its predetermined time interval, 25 whereupon winding W1 picks up to complete its own stick circuit, which holds winding W1 energized when relay TER opens its contact 6. When section F—G is vacated, relay 2TR and winding 30 W2 pick up to restore the apparatus to the normal position.

The operation of the apparatus embodying my invention for both a long and short westbound train is substantially similar to the operation just described for a long and a short eastbound train, and it is thought that this latter operation for the westbound train will be readily apparent from the foregoing description for the operation of the eastbound train together with an inspection of the drawing without further detailed 40 explanation.

It is to be noted that relay TER functions to restore winding W1 or W2 to its normal condition when a train enters the control section to initiate the operation of signal S, but which 45 train reverses its direction and vacates that section without proceeding across the intersection. That is to say, since relay TER is energized over its first energizing circuit when winding W1 or W2 is released and both track relays 1TR and 2TR are picked up, it follows that when an eastbound train, for example, reverses direction in section D—E and vacates that section after having initiated the operation of signal S, then relay TER is energized and completes at the end 55 of its predetermined time interval the pick-up circuit for winding W1 whereupon winding W1 is restored to its normal condition and the operation of signal S is terminated.

It should further be noted that although the 60 control track sections cannot be extended to the intersection, the intersection is protected for a predetermined time interval after the train vacates the control section on the approach side of the intersection, and that directional control 65 of the signal is established.

Although I have herein shown and described only one form of apparatus embodying my invention, it is understood that various changes and modifications may be made therein within 70 the scope of the appended claims without departing from the spirit and scope of my invention.

Having thus described my invention, what I claim is:

1. In combination, a stretch of railway track 75

divided into a first section and a second section separated from each other by an intermediate section, a signal, a first relay operable by a car entering said first section, a second relay operable by a car entering said second section, operating means controlled by each of said first and second relays for operating said signal for railway traffic approaching the intermediate section in either of said first and second sections, a timing device effective when operated to control said operating means to terminate operation of said signal, and circuit means controlled by said operating means and including a back contact of the track relay associated with the section on the receding side of the intermediate section for operating said time element device whenever the section in approach of the intersection is vacated provided the other section is occupied, the characteristics of said timing device being such as to maintain operation of said signal by said operating means during the time interval required for a car to traverse said intermediate section.

2. In combination, a stretch of railway track divided into two outer sections separated from each other by an intermediate section intersected by a highway, a highway crossing signal positioned at such intersection, a first track relay for said first section, a second track relay for said second section, operating means governed by said track relays for operating the signal when a train approaches the intersection, a time element device having a contact closed at the expiration of a predetermined time interval after energization thereof, circuit means for energizing said time element device governed by said track relays and by said operating means and effective when both said first and said second sections are unoccupied, other circuit means for energizing said time element device governed by said operating means and including a front contact of the track relay associated with the section on the approach side of the intersection and a back contact of the track relay associated with the section on the receding side of the intersection, and means controlled by said contact of said time element device for terminating operation of said signal by said operating means whereby to insure the operation of said signal for said predetermined time interval after said approach section is vacated, said predetermined time interval being selected to provide operation of said signal for the time interval required by a car moving at a normal rate of speed to traverse said intermediate section.

3. In combination, a stretch of railway track divided into two outer sections separated from each other by an intermediate section intersected by a highway, a highway crossing signal positioned at such intersection, two track relays one for each of said two outer sections, an interlocking relay having two windings one for each of said two track relays, operating circuit means

for operating said signal governed by each of the two windings of said interlocking relay, stick circuit means for normally energizing each winding of said interlocking relay governed by its associated track relay, a time element device having a contact closed in a predetermined period of time after energization thereof, pick-up circuit means for energizing each winding of said interlocking relay governed by the associated track relay and by said contact of said time element device, and circuit means for energizing said time element device governed by said interlocking relay and including both front and back contacts of said two track relays arranged in such manner that said timing device is energized whenever either section on the approach side of the intersection is vacated regardless of traffic conditions in the other section on the receding side of the intersection, whereby energization of the winding of said interlocking relay associated with the track relay of said approach section is avoided for said predetermined time interval to insure operation of said signal for the time interval required by a car moving at a normal rate of speed to traverse said intermediate section.

4. In combination, a stretch of railway track divided into two outer sections separated from each other by an intermediate section intersected by a highway, a highway crossing signal located at such intersection, two track relays one for each of said two outer sections, an interlocking relay having two windings one for each of said two track relays, a stick circuit controlled by each track relay for normally energizing the associated winding of said interlocking relay, means controlled by each of said two windings of the interlocking relay for operating said signal, a time element device having a contact operated from a normal to an operated position after a predetermined time interval of energization of such device, three alternate circuit paths for energizing said time element device one path of which includes a back contact of either of the two windings of said interlocking relay and a front contact of each of said two track relays, each of the other two circuit paths of which includes a full-released back contact of one or the other winding of said interlocking relay and a front contact of the track relay associated with such full-released winding as well as a back contact of the other track relay, and means controlled by each of said two track relays and by said contact of said time element device for establishing a pick-up circuit for the winding of said interlocking relay associated with the one of said two track sections occupied by a train in approaching the intersection, whereby to insure the operation of said signal for the time interval required by a car moving at a normal speed to traverse said intermediate section.

CHARLES W. BELL.
